UNITED STATES PATENT OFFICE.

EDWARD A. JOHNSTON, OF STERLING, ILLINOIS, ASSIGNOR TO INTERNATIONAL HARVESTER COMPANY, A CORPORATION OF NEW JERSEY.

CORN-PLANTER.

No. 825,059.

Specification of Letters Patent.

Patented July 3, 1906.

Application filed December 28, 1905. Serial No. 293,545.

To all whom it may concern:

Be it known that I, EDWARD A. JOHNSTON, a citizen of the United States, residing at Sterling, in the county of Whiteside and State of Illinois, have invented a new and useful Improvement in Corn-Planters, of which the following is a complete specification.

This invention relates to check-row corn-planters, and has for its object the improvement of the mechanism which actuates the seed-plate, also an improved construction of seed-valve in the seed-tube and means for operating same, and a cheap and effective frame construction, including means for adjusting the tongue in its connection therewith.

Referring to the accompanying drawings, Figure 1 represents a plan of a corn-planter embodying my improvements. Fig. 2 represents a side elevation of a complete machine. Fig. 3 is a central longitudinal section. Fig. 4 is a plan view of the check-head and seedbox-support on the right-hand side of the machine, the seedbox and cut-off plate being removed to more clearly show the manner of operating the seed-plate and with the check-lever being shown in its normal forward position. Fig. 5 is a corresponding view showing the check-lever moved to its rearward position. Figs. 6 and 7 represent similar views of corresponding parts on the left-hand side of the planter, Fig. 6 showing the check-lever in normal forward position and Fig. 7 in its rearward position, these views being more particularly designed to show the connecting of the shake or connecting rod with its connecting members on the opposite side of the machine. Fig. 8 is a vertical longitudinal section taken through the right-hand seedbox and subjacent parts as indicated by the line 8 8 of Fig. 4. Fig. 9 is a transverse vertical section of the same seedbox, taken on the line 9 9 of Fig. 4. Figs. 10 and 11 represent, respectively, a longitudinal and a transverse vertical section taken through the left-hand seedbox and correspond with Figs. 8 and 9, the views being taken, respectively, on the lines 10 10 and 11 11 of Fig. 6. Fig. 12 is a detail reverse plan of the cut-off plate with a portion of the seed-plate shown in dotted lines in proper relation thereto. Figs. 13 and 13' are detail views in side elevation, showing, respectively, the spring-knocker and cut-off

finger in relation to the seed-plate. Fig. 14 is a view illustrating the hinge connection of the supporting-bar and doffer for the wire guide-rollers. Fig. 15 represents a transverse horizontal section through the runner-shank, taken on the line 15 15 of Fig. 8. Fig. 16 is a detail transverse section through the reel-shaft and reel and driving parts therefor, taken on the line 16 16 of Fig. 2. Fig. 17 illustrates the construction of the device for adjusting the length of the shake-rod. Fig. 18 is a detail section taken on the line 18 18 of Fig. 1, showing the adjustable connection of the runner-frame with the wheel or main frame of the planter. Fig. 19 represents a fragmentary plan of the bottom of the seed-hopper, the view being designed to show the construction and arrangement of the seed-plate, the pawl for actuating same, and the pawl-detention plate for controlling the time of engagement of the said pawl with the seed-plate. Fig. 20 is a similar view showing the pawl-detention plate adjusted to a position to permit of the maximum movement of the seed-plate, and Fig. 21 represents a detail perspective view of the pawl-detention plate.

Referring to the accompanying drawings, the main frame is formed of a bar 1, bent in a U-shaped form with its transverse portion at the rear of the machine, this bar being mounted on the stationary main axle 2, on which is journaled the supporting and covering wheels 3. To the forward ends of the side members of the bar 1 of the main or wheel frame is adjustably attached the front or runner frame 4, the attachment being effected by means of the casting 5 (see Fig. 18) and the bolts 6. In the flange 5' of this casting is formed a forward bolt-hole 5² and a series of holes 5³, radially disposed with respect to the first-mentioned bolt-hole. The forward bolt-hole 5² forms the pivotal center about which adjustment of the angle of the runner-frame is made with respect to the main frame, these bolt-holes registering with corresponding apertures in the front ends of the U-shaped bar 1 of the main frame.

The main or cross bar of the runner-frame 4 consists of a pipe with suitable attachments for connecting the associated parts. Intermediate of the length of said runner-frame on the brackets 7' is pivotally mounted the tongue, the tongue being braced by means of

the diagonally-extending brace-rods 8, which have their pivotal connection with the runner-frame transversely coincident with the pivotal centers of the tongue and preferably coincident with the pivotal center of adjustment between the main and runner frame. On the rear end of the tongue is pivotally mounted the tongue-controlling lever 9, which operates with a suitable quadrant 10, fixed also on the tongue and in proper relation to said lever. The lever 9 is bent below its pivotal point, the rearwardly-extending portion 9' slidably engaging at its rear end the fulcrum-block 11, (see Fig. 3,) which pivots on the axle 2 of the main frame. A spring 12 is interposed between the lever 9 and the runner-frame 4 in such a manner as to exert a stress tending to counterbalance the forward end of the tongue. As the lever is moved forwardly, its rear end in the fulcrum-block 11 being held stationary, the rear end of the tongue will be depressed and the forward end raised, while movement rearwardly of the lever will have a reverse effect.

25 The rocking scraper-bar 13, (see Figs. 1, 2, and 3,) carrying the scraper-blades 13', is operated by the foot-lever 14. The reel 15 is mounted on a suitable shaft 15' in the bracket 16 and is driven from one of the supporting-wheels by a sprocket-chain connection 17 with the reel-shaft, as clearly shown in Figs. 1, 2, and 16. As no claim to novelty is made in the scraper device and reel mechanism, a detailed description thereof is deemed unnecessary.

30 To the outer ends of the pipe cross-bar forming the runner-frame 4, on the under side thereof, are secured the shanks 18 of the runners, which in connection with the runner-shoes 19 constitute the usual furrow-opening device. The runner-shoes 19 are of the usual form, the upper end of each being secured to a forwardly-extending lug 18' on the upper end of said shank. The rear side of 45 the runner-shank is cored out and extended upwardly to the seedbox, thus forming a seed conduit or tube 20, leading from the seedbox down to the heel of the shank 18. The runner-shank is secured to the runner-frame 50 4 by means of the bolts 21 and 22, these bolts also securing to the runner-frame the check-head base 23.

55 On the upper face of the check-head base is secured, by means of the bolt 22 and the check-lever spindle 24, the seedbox-support 25, as shown in Figs. 8 and 11, inclusive. The check-head base 23 projects beyond the end of the runner-frame, is triangular in shape, and supports at its outer end the 60 wire guide-rollers 26 and 26'. The seedbox-support 25 consists of three equiangularly-disposed legs projecting outwardly and upwardly from the check-head support, to which it is secured, the upper end of the legs 65 terminating in a rim 25', having the lugs 25'

formed thereon. On this rim 25' is fixed the seedbox 27. The ring 28, which is provided with lugs 28', corresponding with those on the rim 25', is secured to the bottom of said seedbox in order to afford effective means for fastening the seedbox in position. In the bottom of the seedbox 27 is fixed the conical-shaped cap-deflector or cut-off plate 29, the check-lever spindle 24 serving as a support for same, while a shoulder on the upper end 75 of said spindle in connection with the nut 30 holds the plate firmly in position.

The cut-off plate and seed-ejector (see Figs. 12 and 13) are of the usual construction having the housing 29' extending to the wall 80 of the seedbox, and within this housing is mounted the cut-off finger 31 and the hammer 32, both of which are spring-held to their work and perform the well-understood function of such elements. Beneath the cut-off plate 29 and supported by the rim 25' of the seedbox-support 25, as shown in Figs. 8 to 11, is the annular-shaped seed-plate 33, provided on its outer margin with the seed-cells 33' and on its inner margin with the 85 ratchet-teeth 33''. The seed-plate fits closely within the rim 25' and also closely beneath the cut-off plate 29. The cut-off plate, however, except at its housing, extends with its outer margin substantially flush with the bottom of the seed-cells 33', so that the cells project beyond the margin of said cut-off plate. The mutual relation of the cut-off and seed plates, as well as the cut-off finger 31 and spring-hammer 32, is clearly shown in Figs. 100 12, 13, and 13', the direction of rotation of the seed-plate being indicated by the arrows in these figures. It is apparent that as the seed-plate is made to rotate in the direction indicated the spring-actuated cut-off finger 105 31 will prevent the cells 33' from carrying more than a single grain of corn beneath the housing 29', and the spring-actuated hammer 32 will insure the grain of corn being dislodged from its cell and forced down into the 110 seed-tube 20. A portion of the bottom flange 25' of the rim 25' is cut away beneath the housing 29' on the cut-off plate directly beneath the cells on the seed-plate, thus 115 forming a seed-outlet 34 from the bottom of the seedbox, as shown in Figs. 8 and 10 and in black in Figs. 4 to 7. This seed-outlet communicates with the seed-tube formed in the shank 18, the upper extension of said shank connecting with the rim 25' of the seedbox-support by means of the bolt 35, which engages one of the lugs 25'' on said rim.

120 The seed-plate 33 is operated as follows: On the spindle 24 is sleeved the check-lever 36', constructed, preferably, of two parts. 125 The arm portion 36 of the lever rests upon the foot of the seedbox-support 25, and above this is the head portion 37. This head portion of the lever is provided with the laterally-projecting arms 37' and 37'', the arm 130

37' having formed integral therewith the depending shoulders 37', which renders the head portion 37 of the check-lever movable rearwardly independent of the arm portion 36 and also compels the said head portion to be moved rearwardly by the arm portion against the action of the spring 38, which is interposed between the head portion and one of the legs of the seedbox-support 25. A boss 39 extends upwardly from the outer end of the arm 37', and on top of this boss is pivotally mounted the pawl 40, arranged to engage the teeth 33² on the inner face of the seed-plate 33. A coil-spring 41 is interposed between the pawl 40 and an upwardly-projecting ledge 42, formed also on the arm 37'. It is obvious that as the check-lever arm 36 is pulled rearwardly by the tappet-wire 43 in the forward movement of the machine the head portion of the lever will also be moved rearwardly against the action of the spring 38, which movement will cause the pawl 40 to engage the teeth on the seed-plate and cause the seed-plate to rotate from the position shown in Fig. 4 to that shown in Fig. 5 on the right-hand side of the machine and, as shown in Fig. 6, to that shown in Fig. 7 on the left-hand side of the machine. As soon as the tappet-wire releases the lever-arm 36 the spring 38 will immediately restore the parts to the normal forward position.

The dropping mechanism is adjusted to deposit the required number of grains by varying the extent of movement of the seed-plate, 35 and the extent of movement of the seed-plate is regulated by holding the pawl 40 out of engagement with the seed-plate teeth 33² for a greater or less portion of the movement of said pawl. The time of engagement of the 40 pawl 40 with the seed-plate is controlled by means of the pawl-detention plate 44, which is adjustable with respect to the pawl and is secured by means of screws to the rim 25' of the seedbox-support. This plate (shown in 45 Figs. 4, 9, and 19 to 21) lies beneath the said rim 25', extends inwardly and is provided at its inner edge with the upwardly-projecting flange 44³, which is contacted by the pawl 40. A series of holes 45 in the rim provides for peripheral adjustment of said plate on its support. As will appear from an inspection of 50 Figs. 4 to 7 and 19 and 20, the detention-plate 44 will hold the pawl out of engagement with the seed-plate teeth to a greater or less 55 degree, depending on its position. If said plate be adjusted to the dotted-line position, 44' (see Fig. 4) will hold the pawl out of engagement with one of the teeth, causing the seed-plate 33 to move a less distance by one 60 cell, and thereby drop one seed less. If, on the other hand, the plate is adjusted to the dotted-line position marked 44², the pawl 40 will engage an additional tooth and drop an extra seed. In Fig. 19 the plate 44 is so adjusted that the pawl 40 moves the seed-plate 65

over the space of one seed-cell, while in Fig. 20 its position is such that the said pawl 40 is permitted to engage the teeth of the seed-plate earlier and move same over the space of three seed-cells. In this manner the plate 70 may be adjusted to drop any number of kernels of corn from one to three, and as the parts for effecting such adjustment are outside the seedbox and easy of access the adjustment can be made with little trouble. 75 The same result, it is evident, could be attained if the pawl instead of the plate were made adjustable.

The following valve mechanism in the seed-tube 20, with means for operating same, is 80 provided: A valve member 46 is pivoted at 47 at the forward side of the seed-tube in the shank 18, this member extending downward and sweeping with its lower end the ledge 18², formed in the lower end of the seed-tube 20 85 and at the heel of the runner-shank. On the head portion 37 of the check-lever is formed the slotted cam projection 48, this cam projection and the arm 37² being independent and extending in opposite directions on the 90 right-hand side of the machine, but on the left-hand side extend in the same direction and merge with each other. The slot in this cam projection engages a roller 46' on the upper end of the valve member 46 and actuates 95 same when the check-lever is moved. At the lower end of the seed-tube 20 is pivotally mounted at 49 the spring-held second valve member 50, curved forwardly intermediate of its length to form the knee 50' thereof, 100 which contacts the first-described valve member whenever same is swung rearwardly. It will thus be seen that as the check-lever arm 36 is moved rearwardly by the tappet-wire the pawl 40 will actuate the seed-plate 105 in the manner above described, while the cam-slot 48 will swing the valve member 46 rearwardly at its lower end and dislodge the grain on the ledge 18². In this movement the valve member 46 will contact the knee 110 50' of the member 50, thus forming an upper valve in the seed-tube, which will remain closed during the remainder of the movement. As soon as the check-lever is released it will be forced quickly back to normal forward position, the valve member 46 being 115 also returned by the cam 48. The kernels of corn will thus be allowed to drop down upon the ledge 18², the rear valve member 50 pressing with its lower end against said ledge, 120 thus forming a lower valve, on which the corn is held until again dislodged by the member 46 in the succeeding dropping operation.

To connect the two check-levers and cause 125 them to operate the seed-plates 33 in unison with each other, a shake-rod 51 is interposed between the head portion 37² of said levers. This shake-rod is made adjustable in length by means of the coupling 52, the small end 130

52' of which is threaded to receive one part of the shake-rod, while the barrel portion 52² is provided with a set-screw 53 to secure the other part of said shake-rod. Such construction of the shake-rod will permit of easy and accurate adjustment of same to compensate for wear and also permit of proper adjustment to the head portion of the check-lever when the distance between the seedboxes is varied.

In order to readily engage and disengage the check-wire from the check-head, the outer guide-rollers 26' are mounted on the hinged bar 54, which is adapted to fold downwardly, as indicated by the dotted-line position of the detail shown in Fig. 14. The spring 55, in conjunction with the bell-crank 56 and the link 57, operates to effect the release of said bar 54 or to lock it in its normal position.

What I claim as my invention, and desire to secure by Letters Patent, is—

1. In a corn-planter, in combination, a seed-plate, a check-lever actuated by a tappet-wire, and a pawl mounted upon said check-lever for actuating said seed-plate.

2. In a corn-planter, in combination, a seed-plate, a two-part check-lever actuated by a tappet-wire, and a pawl mounted upon said check-lever for actuating said seed-plate.

3. In a corn-planter, in combination, a seed-plate, a two-part check-lever actuated by a tappet-wire, the said seed-plate and lever having a common axis of movement.

35 4. In a corn-planter, in combination, an annular-shaped seed-plate provided at its outer margin with seed-cells and on its inner margin with ratchet-teeth, a check-lever actuated by a tappet-wire, and a pawl mounted upon said check-lever and arranged to engage the teeth on and actuate said seed-plate.

5. In a corn-planter, in combination, a seedbox, an annular-shaped seed-plate, a two-part check-lever comprising an arm and a head portion, a cam-slot formed integral with said head portion, a runner-shank constituting a seed-tube, a seed-valve in said shank, and an operative connection between said cam and seed-valve.

50 6. In a corn-planter, in combination, a seedbox, a seed-plate, a two-part check-lever actuated by a tappet-wire and consisting of a head and an arm portion relatively movable to a limited extent with respect to each other, the said seed-plate and the two parts of the check-lever movable about a common axis, and a pawl mounted on the head portion of said check-lever for engaging and actuating the seed-plate.

60 7. In a corn-planter, in combination, seedboxes, seed-plates operating therein, two-part check-levers consisting each of a head and an arm portion relatively movable to a limited extent with respect to each other, a pawl mounted on the head portion of each

check-lever for actuating the seed-plates, and a shake-rod connecting the said check-levers.

8. In a corn-planter, in combination, seedboxes, seed-plates arranged therein, two-part check-levers consisting each of a head and an arm portion relatively movable to a limited extent with respect to each other, a pawl mounted on the head portion of each check-lever for actuating the seed-plates, and a shake-rod adjustable in length connecting the head portions of said check-levers.

9. In a corn-planter, in combination, seedboxes, seed-plates arranged therein, two-part check-levers consisting each of a head and an arm portion, the head portion being movable rearwardly independent of the arm portion, springs tending normally to hold said head portions in their forward position, an arm formed integral with each head portion, an adjustable shake-rod connecting said arms, and a pawl mounted on each of said head portions for actuating the seed-plates.

10. In a corn-planter, in combination, a seedbox, an annular-shaped seed-plate, a two-part check-lever comprising an arm and a head portion, the said head portion being provided with means for engaging the arm portion, a pawl mounted upon the head portion for actuating the seed-plate, a cam in connection with said two-part lever, a runner-shank constituting a seed-tube, and a seed-valve in said shank, said valve consisting of a forward, pivotally mounted, cam-actuated member extending upwardly and engaging the cam on the two-part check-lever, and a coöperating spring-held forwardly-curved valve member located in the heel of said shank.

11. In a corn-planter, in combination, a seedbox, an annular-shaped seed-plate, a two-part check-lever comprising an arm and a head portion, a cam-slot formed integral with said head portion and extending in part eccentric and in part concentric with respect to the center of movement of said check-lever, a runner-shank constituting a seed-tube, and a seed-valve in said shank, one member of said valve extending upwardly and engaging the cam-slot in said check-lever.

12. In a corn-planter, in combination, a seedbox, an annular-shaped seed-plate, a two-part check-lever comprising an arm and a head portion, a cam-slot formed integral with said head portion and formed in part eccentric and in part concentric with respect to the center of movement of said check-lever, a runner-shank constituting a seed-tube, a ledge formed therein at the heel of said shank, said ledge with the second valve member constituting the lower or primary valve, a valve member pivotally mounted on the forward side of said seed-tube and extending upwardly and engaging said cam-slot, the said member being arranged to

sweep with its lower end the ledge and thus dislodge the seeds therefrom, a second spring-held valve member pivotally mounted at the rear of the seed-tube and near the bottom thereof, the second member being provided intermediate of its length with a forwardly-curved portion which forms, in conjunction with the said first valve members, a secondary or upper seed-valve, the lower end of the second valve member normally resting against the ledge in the seed-tube and thereby closing the lower or primary seed-valve.

13. In a corn-planter, in combination, a seedbox, an annular-shaped seed-plate provided with seed-cells and ratchet-teeth, a check-lever actuated by a tappet-wire, a pawl mounted on said check-lever for operating the seed-plate, and means for regulating the extent of effective movement of said pawl in its action upon said seed-plate.

14. In a corn-planter, in combination, a seedbox, an annular-shaped seed-plate provided with seed-cells and ratchet-teeth, a check-lever actuated by a tappet-wire, a pawl mounted on said check-lever for operating the seed-plate, and means beneath and independent of said seedbox for regulating the extent of effective movement of said pawl in its action upon said seed-plate.

15. In a corn-planter, in combination, a seedbox, an annular-shaped seed-plate provided with seed-cells and ratchet-teeth, a check-lever actuated by a tappet-wire, a pawl mounted on said check-lever for operating the seed-plate, and a pawl-detention plate, the said pawl and detention-plate being adjustable in their operative relation with respect to each other.

16. In a corn-planter, in combination, a

seedbox, a seedbox-support, an annular-shaped seed-plate provided on its outer margin with seed-cells and on its inner margin with ratchet-teeth, a check-lever actuated by a tappet-wire, a pawl mounted on said check-lever for operating the seed-plate, and a pawl-detention plate secured to the under side of said seedbox-support and peripherally adjustable thereon.

17. In a corn-planter, in combination, a seedbox, a cap-deflector, an annular-shaped seed-plate, and means arranged to engage the inner edge of said seed-plate and impart an intermittent movement thereto.

18. In a corn-planter, in combination, a seedbox, a cap-deflector, an annular-shaped seed-plate, a check-lever, and a pawl controlled by said check-lever for actuating said seed-plate.

19. In a corn-planter, in combination, a seedbox, a cap-deflector, an annular-shaped seed-plate provided on its outer margin with seed-cells and on its inner margin with ratchet-teeth, a check-lever, and a pawl mounted upon said check-lever and controlled thereby for actuating said seed-plate.

20. In a corn-planter, in combination, a seedbox, a cap-deflector, an annular-shaped seed-plate provided on its outer margin with seed-cells and on its inner margin with ratchet-teeth, a check-lever, and a pawl mounted upon said check-lever for actuating said seed-plate, said pawl lying within and in the plane of said seed-plate.

EDWARD A. JOHNSTON.
